US00D938114S

(12) **United States Design Patent** (10) Patent No.: **US D938,114 S**
Yan et al. (45) Date of Patent: ** Dec. 7, 2021

(54) **INTELLIGENT CLEANING ROBOT**

(71) Applicant: **SUNGROW POWER SUPPLY CO., LTD.**, Anhui (CN)

(72) Inventors: **Baofei Yan**, Anhui (CN); **Lei Li**, Anhui (CN); **Rui Wang**, Anhui (CN); **Gaozhou Tao**, Anhui (CN)

(73) Assignee: **SUNGROW POWER SUPPLY CO., LTD.**, Anhui (CN)

(**) Term: **15 Years**

(21) Appl. No.: **29/697,835**

(22) Filed: **Jul. 11, 2019**

(30) **Foreign Application Priority Data**

Mar. 22, 2019 (CN) 201930122769.4

(51) **LOC (13) Cl.** **15-05**

CLAIM

The ornamental design for an intelligent cleaning robot, as shown and described.

DESCRIPTION

FIG. 1 is a front view of an intelligent cleaning robot;

FIG. 2 is a rear view thereof;

FIG. 3 is a left view thereof;

FIG. 4 is a right view thereof;

FIG. 5 is a bottom view thereof;

FIG. 6 is a top view thereof;

FIG. 7 is a perspective view thereof;

FIG. 8 is an enlarged view of FIG. 5;

FIG. 9 is an enlarged view of FIG. 6;

FIG. 10 is a partial enlarged view of an area identified as 10 in FIG. 2; and,

(Continued)

FIG. 11 is a partial enlarged view of an area identified as 11 in FIG. 3.

1 Claim, 11 Drawing Sheets
